UNITED STATES PATENT OFFICE.

ABRAHAM RAUCH, OF NEW YORK, N. Y.

ELECTRICAL SHOOTING BOARD.

Application filed March 23, 1922. Serial No. 546,147.

To all whom it may concern:

Be it known that I, ABRAHAM RAUCH, a citizen of the United States, and a resident of the city of New York, borough of Bronx, 5 in the county of Bronx and State of New York, have invented a new and Improved Electrical Shooting Board, of which the following is a full, clear, and exact description.

This invention relates to an electrical 10 shooting board, and has for an object the provision of a shooting board which is adapted particularly for use in connection with amusement parks, and is presented in the form of a game in which a plurality of 15 contestants may compete.

Another object resides in the provision of a simple construction and electrical circuit apparatus so that the operation requires a minimum amount of expenditure of time 20 and labor in the construction and in the repair of the device.

A further object resides in the provision of such an electrical combination of apparatus as will insure an efficient operation 25 at all times.

A still further object resides in the provision of a combination of elements whereby whenever a successful shot is made a light 30 will be lit and permanently retained in its lighted condition until its circuit is opened, to indicate the fact that such a shot has been made.

Another object resides in the particular 35 construction and arrangement of parts which are hereinafter described and claimed and shown in the accompanying drawings.

The invention is illustrated in the drawings, of which—

Figure 1 is a front view of the board with 40 the parts cut away.

Fig. 2 is a section taken on the line 2—2 of Fig. 1.

Fig. 3 is a horizontal section taken on the line 3—3 of Fig. 1.

Fig. 4 is a circuit diagram of the apparatus.

The form of the invention shown in the drawings is a preferred form, although it is understood that modifications in the construction and arrangement of the parts and in the character of the materials used may be adopted without departing from the spirit of the invention.

I provide, in accordance with the preferred application of my invention, a board 55 in the form of a receptacle or body portion

1 which has a cover or door 2 pivoted thereto. The body portion or receptacle has disposed on its rear inner face 3 a plurality of pairs of contacts 4 and 5 in the form of 60 spring plates which are spaced one back of the other, closely adjacent, so that when one plate is moved ever so slightly it will contact with the other and make an electrical circuit which is properly connected to these plates. Each pair of plates is disposed back of an aperture, such as 6, in the door or cover of the board.

The main idea of the game is for the player to aim so accurately that the missile will enter the aperture 6 and strike the first contact 5. The upper edge of the door or cover 2 is provided with a plurality of openings, such as the rectangular openings 7, in which suitable transparencies, such as glass 8, may be disposed; and back of these openings 7 are disposed lamps 9, preferably supported on a shelf 10 fastened to the box or receptacle 1 in any desired manner. There are as many 80 apertures or openings 7 as there are apertures or openings 6, and corresponding thereto, as many lamps 9 as there are openings 6. The openings 6 are numbered in any desired manner, and the transparencies 8 are also provided with numbers corresponding to the numbers of the openings 6. Whenever a missile enters any opening, which corresponds to a bull's eye or perfect hit, the lamp corresponding to that opening is illuminated.

The illumination of the lamp is effected in the following manner, as illustrated in the circuit diagram shown in Fig. 4. A battery 11 is provided, and one side of it 95 is connected respectively through the wires 12, 13, 14 and 15 to the respective contacts 5. The respective contacts 4 are connected by wires 16, 17, 18 and 19 to a plurality of automatic electrical drops, such as 20, the 100 other sides of which are connected to the battery. Therefore, whenever any pair of contacts 4 and 5 are brought together by the impact of a missile, the circuit through the battery 11 and the drops 20 momentarily closes for a sufficient length of time, whereby the drop will actuate to close another circuit through the battery, the drop and wires such as 21, 22, 23 and 24 leading to the respective lamps 9, the other 110 sides of the lamps being connected by a wire 25 to the other side of the battery 11.

In other words, the momentary making of a circuit by the impact of the missile will cause the permanent establishment of the light circuit corresponding to the particular contacts hit, indicating the fact that a particular bull's eye aperture has been entered by a missile. The drops 20 are of any standard type, the particular construction of them not being important except that the energization of them momentarily will cause a shutter or bar to drop and make a permanent closure. This closed circuit established by drops can then be opened by restoring the drops to their normal position.

It will thus be seen that I have provided a simple and efficient apparatus the door 2 being so pivoted that it can be opened to remove the missiles or other débris from within the cabinet. If desired, the cabinet may have no bottom, so that the missiles can drop out of the cabinet and be collected in any suitable receptacle. By

merely opening the door, access can be had to the interior. The simplicity of the device and the circuits involved render the liability of getting out of repair practically negligible.

What I claim is:

An electrical shooting board which comprises a cabinet having a pivoted door or cover in which a plurality of bull's eye apertures are located, a plurality of pairs of spring contact plates disposed on the rear wall of the board or receptacle back of the bull's eye apertures, a shelf in the upper portion of the board, a plurality of lamps mounted on the shelf, said board having a plurality of openings along the upper edge of the door in front of the lamps, and a transparency in each of said lamp openings having a number thereon corresponding to the numbers disposed adjacent each of the bull's eye openings.

ABRAHAM RAUCH.
